EARTH ANCHOR

Clyde E. Clapper, Rte. 1, Box 73, Blue Springs, Mo.

Filed July 10, 1959, Ser. No. 826,332

9 Claims. (Cl. 189—92)

This invention relates to new and useful improvements in earth anchors, and has particular reference to an earth anchor having a stake-like body or housing and ground-engaging means normally retracted within the housing and which are extendable laterally from the housing after said housing has been inserted in the earth.

An important object of the present invention is the provision of an earth anchor of the general class described having novel means providing for maximum extension of said ground-engaging means from said housing, and hence for maximum holding power of the anchor. The actual limitation of the degree of extension and area of the extended ground-engaging means is determined by the size of the ground-engaging means which may be fully retracted into the housing of the anchor preparatory to inserting the anchor into the ground. The accomplishment of this object therefore involves a novel arrangement of parts whereby ground-engaging means, constituting a pair of elongated flukes, of maximum length may be retracted into and extended from a body member of a given size.

Another object is the provision of an earth anchor of the class described wherein the level of the ground-engaging flukes is closer to the bottom of the housing than in previous anchors of this type. This provides the greatest possible holding power when setting the anchor at any given depth, since the flukes are thereby positioned farther below the surface of the ground.

A further object is a novel arrangement of parts whereby the ground-engaging flukes are solidly supported relative to the housing at all times, both during extension and retraction thereof, and also while fully extended, whereby to prevent damage to the anchor parts which might otherwise occur as a result of misarrangement of the flukes relative to the body.

Other objects are simplicity and economy of construction, efficiency and dependability of operation, ease of assembly and servicing, and adaptability for use in a wide variety of applications.

With these objects in view, as well as other objects which will appear in the course of the specification, reference will be had to the drawing, wherein:

Fig. 1 is a side elevational view, partially broken away, of an earth anchor embodying the present invention, shown inserted operatively in the earth with the ground-engaging flukes fully extended,

Fig. 2 is an enlarged longitudinal sectional view of the anchor as shown in Fig. 1, with parts left in elevation and parts broken away,

Fig. 3 is a view similar to Fig. 2 but showing the flukes fully retracted within the housing,

Fig. 4 is a fragmentary sectional view taken on line IV—IV of Fig. 3, with the housing in section and the remaining parts left in elevation, and

Fig. 5 is a sectional view taken on line V—V of Fig. 2, with parts left in elevation.

Like reference numerals apply to similar parts throughout the several views, and the numeral 2 applies to a

2

tubular body or housing formed of steel or other suitable material. The lower end of said housing is closed by an end fitting including a bottom plug 4, the external surface of which is spherically curved, and the upper surface of which has a countersunk socket 6 formed therein. A pair of tongues 8 formed integrally with plug 4 extend upwardly into housing 2. Externally said tongues are cylindrically curved and engage the housing wall at diametrically opposite sides thereof. The inner or confronting surfaces of said tongues are planar, being parallel to each other and to the axis of the housing. Plug 4 is secured in the housing by a pair of screws 10 (see Fig. 4) extending through the housing wall and threaded into tongues 8. A flat screw plate 12 is disposed between the upper end portions of tongues 8, at right angles to the housing axis, and is provided with a central threaded aperture 14 therein. Opposite edge portions of said screw plate are carried for horizontal sliding movement in grooves 16 (see Fig. 4) formed in the confronting faces of the tongues, and the housing secures said plate against removal from said grooves. The plate must of course be positioned in the grooves before the tongues are inserted into the housing.

The upper end of housing 2 is closed by a top plug 18 secured therein by screws 20, said plug having a central aperture 22 formed therein. A stem 24 is carried for rotation and axial sliding movement in aperture 22. An eye member 26 is affixed to the upper end of said stem, said eye serving both as a means for turning said stem to operate the flukes as will be described, and also as a means for attaching a guy line or the like which is to be anchored relative to the ground by means of my device. Stem 24 extends downwardly through the housing coaxially therewith. The lower end portion of said stem is externally threaded at 28 with right-hand threads, and is screwed into and through aperture 14 of screw plate 12, which is correspondingly threaded. The lower end portion of said stem is also tubular, having an axial socket 30 formed therein from the lower end thereof, said socket being threaded with left-hand threads.

Threaded into socket 30 is a correspondingly left-hand threaded spindle 32, said spindle extending downwardly from the stem between tongues 8. Rigidly affixed to the lower end of said spindle is a cross head indicated generally by the numeral 34 and including a horizontally extending bar 36. The ends of said bar are planar, and bear slidably against the confronting faces of tongues 8, whereby rotation of the cross head and spindle about the housing axis is prevented. Extending oppositely from the midpoint of bar 36 are a pair of horizontal stub shafts 38, the outer ends of which rest in sliding engagement with the inner surface of housing 2. Formed in the lower side of each of said stub shafts, adjacent the outer end thereof, is a notch 40, the purpose of which will presently be described. Depending from cross head 34 and rigidly connected thereto is a short finder pin 42 coaxial with the housing, and which is adapted to be received snugly in socket 6 of bottom plug 4, as will be described.

Each of stub shafts 38 supports a fluke 44 comprising an elongated strip of plate metal having a width corresponding to the distance between the confronting faces of tongues 8, and being cylindrically curved from end to end. Referring principally to Figs. 3 and 4, it will be seen that when the flukes are retracted within housing 2 they are disposed generally vertically, with their concave surfaces facing outwardly, and their convex surfaces abutting each other at the centerline of the housing. Adjacent its upper end, each fluke has a hole 46 formed therethrough, through which the corresponding stub shaft 38 extends to support the fluke. Thus the fluke may be moved slidably along the shaft, and also, due to the fact that the hole is oversized, may be tilted relative to the

axis of said shaft. The lower end of each of the flukes extends into a hole 50 formed therefor in the wall of housing 2, and is provided with a curved cutting edge 48, which when the flukes are fully retracted as shown in Figs. 3 and 4 is disposed flush with the outer surface of the housing. The two flukes rest respectively on a pair of bevelled lips 52 formed by chamfering the upper surface of bottom plug 4 at diametrically opposite sides thereof.

In the operation of the anchor, it is first inserted, with the flukes retracted, into a hole 54 which has previously been bored in the ground 56 by any suitable means, not shown as it forms no part of the present invention. The present device is not properly termed a stake, as it is not adapted to be driven into the ground by a hammer or the like. It will be seen that by allowing the two flukes to abut each other as shown when fully retracted, the flukes may be of the greatest possible arcuate length for the diameter of the housing. Since this increases the degree or distance to which the flukes may be extended, and the greater extension provides greater holding power of the anchor in the earth, this feature is a substantial improvement over previous anchors of this type wherein a stem or spindle extends between the flukes at all times.

After the anchor has been inserted in ground hole 54, stem 24 is turned in a clockwise direction as viewed from above, either by manual manipulation of eye 26, or with the assistance of a lever bar, not shown, inserted through said eye. This advances the stem downwardly through screw plate 12, by means of threads 28. Simultaneously, spindle 32 is advanced downwardly relative to the stem, since said spindle is threaded oppositely to the stem, and since the spindle is locked against rotation by the sliding engagement of the ends of bar 36 of cross head 34 with tongues 8. Thus cross head 34 is advanced downwardly at a rate equal to the sum of the leads of the stem and spindle threads. Assuming that the two threads have equal leads, the cross head moves at double the rate of the stem. This reduces the stem travel and its maximum extension from the housing, and reduces the number of turns thereof required to extend the flukes.

As the cross head is lowered, stub shafts 38 thereof force flukes 44 downwardly, and the lower ends of said flukes are guided outwardly by bevelled lips 52 of bottom plug 4, and the flukes are extended outwardly through holes 50 of the housing, to the position shown in Figs. 1, 2 and 5. The flukes are advanced along an arcuate path, their final extended position being roughly concentric with their retracted positions in the housing. In this manner, any necessity that the flukes move transversely to their curved planes as they are extended is reduced to a minimum. This reduces the power required to extend said flukes, and provides that the elevation of the anchor in the earth hole 54 will not be changed as the flukes are extended.

As cross head 34 is lowered to extend the flukes as described above, it is guided against lateral deflection in the housing by the fact that the ends of bar 36 thereof engage tongues 8, and the outer ends of stub shafts 38 engage the housing wall. This tends to prevent bending of spindle 32 should, for example, one of the flukes contact a stone or harder ground than the other fluke, which would cause the cross head to be pressed toward one side or the other of the housing. As the flukes near their fully extended positions, finder pin 42 enters socket 6 of bottom plug 4. This further braces the cross head against lateral deflection in the housing due to unequal forces applied to the flukes by loads applied to the anchor.

When the flukes are fully extended, each fluke is supported from below at spaced apart points by bar 36 of the cross head, and by lip 52 of bottom plug 4, and stub shaft 38 of the cross head presses downwardly against the fluke at a point intermediate the two lower support points. Each fluke is thus gripped securely as in a vise. Also, as the angularity of the fluke to shaft 38 changes during

extension of the fluke, the portion of the fluke bounding the lower portion of hole 46 thereof enters and is engaged by notch 49 in the lower edge of shaft 38, as clearly shown in Fig. 2. This corrects a weakness of previous

anchors of this general type, which was that any force tending to pull the anchor from the ground tended to pivot the flukes about lips 52 as a fulcrum, tending to force the inner ends of the flukes upwardly and outwardly, with the result that said flukes moved outwardly along the shafts and damaged or actually tore out the housing wall. Notches 49 prevent any such outward movement of the flukes on the shafts, but do not interfere with the necessary freedom of movement of the flukes relative to said shafts.

15 While I have shown and described a specific embodiment of my invention, it will be readily apparent that many minor changes of structure and operation could be made without departing from the spirit of the invention as defined by the scope of the appended claims.

20 What I claim as new and desire to protect by Letters Patent is:

1. An earth anchor comprising an elongated tubular housing, an end fitting including a bottom plug fixed in the lower end of said housing and a screw plate fixedly 25 associated with said bottom plug and disposed in said housing in spaced apart relation above said bottom plug, said housing having a pair of diametrically opposite openings formed therein just above said bottom plug, a top plug closing the upper end of said housing, a stem 30 disposed axially in said housing, extending through an opening in said top plug and being threaded in said screw plate, a cross head disposed intermediate said screw plate and said bottom plug, and beneath the lower end of said screw, means attaching said cross head to said stem 35 whereby said cross head is advanced toward said bottom plug by turning said stem in said screw plate, and a pair of elongated arcuately curved flukes supported at their upper ends by said cross head for pivotal movement on horizontal axes, and with their lower ends normally registering with said housing openings, said flukes being disposed with their concave sides facing outwardly and their convex sides abutting each other at the centerline of the housing when said flukes are disposed entirely within said housing, whereby as said cross head is lowered toward said bottom plug, said flukes will be extended outwardly through said openings.

2. An earth anchor as recited in claim 1 wherein said end fitting includes a pair of tongues extending from said bottom plug in spaced apart relation, and wherein said screw plate has edge portions thereof slidably engaged 50 in grooves formed horizontally therefor in the confronting surfaces of said tongues, other edges of said screw plate engaging said housing whereby removal of said plate from said grooves is prevented.

3. An earth anchor as recited in claim 1 wherein said means attaching said cross head to said stem is freely rotatable about the axis of said stem, and wherein said end fitting includes tongue members extending between and rigidly interconnecting said bottom plug and said screw plate, said cross head having sliding engagement 60 with said tongue members whereby rotation of the former is prevented, and whereby said flukes are maintained in alignment with said housing openings.

4. An earth anchor as recited in claim 1 wherein said means attaching said cross head to said stem includes a spindle fixed to said cross head and coaxial with said stem, said spindle being threaded to said stem by threads opposite to those connecting said stem to said screw plate, and with the addition of means for preventing rotation 65 of said cross head and spindle relative to said housing.

5. An earth anchor as recited in claim 1 wherein said cross head includes a cross bar extending laterally of said housing and a pair of horizontal stub shafts extending oppositely from said cross bar, each of said flukes having a hole formed therein through which one of said shafts

extends to support said fluke, said hole being of sufficiently large size to permit angular pivoting of said fluke relative to said shaft on a horizontal axis, as well as movement of said fluke longitudinally along said shaft.

6. An earth anchor as recited in claim 5 wherein the outer ends of said stub shafts and said cross bar rest in sliding engagement with said housing and with portions of said end fitting for movement longitudinally of said housing, whereby deflection of said cross head laterally in said housing is prevented.

7. An earth anchor as recited in claim 5 wherein said means attaching said cross head to said stem is freely rotatable about the axis of said stem, and wherein said end fitting includes tongue members extending between and fixed to said bottom plug and said screw plate, and wherein the outer ends of said cross bar rest in sliding engagement with said tongues for movement longitudinally of the housing, whereby to prevent rotation of said cross head in said housing, and wherein the outer ends of said stub shafts are in sliding engagement with the inner surfaces of said housing.

8. An earth anchor as recited in claim 5 wherein each of said stub shafts is provided with a notch in the lower

side thereof adjacent the outer end thereof, whereby as the fluke supported thereby is extended from said housing and consequently tilted about a horizontal axis relative to said shaft, a portion of the fluke bounding the hole through which said shaft extends will enter said notch, whereby said fluke is prevented from moving outwardly relative to said shaft.

9. An earth anchor as recited in claim 1 wherein said cross head and said bottom plug are provided one with 10 a finder pin extending axially of the housing and the other with a matching socket, said pin being sufficiently short as not to hold said flukes out of abutting relation when said flukes are retracted within said housing, whereby as said cross head approaches said bottom plug during 15 extension of said flukes, said finder pin will enter said socket to brace said cross head against deflection laterally of said housing.
